UNITED STATES PATENT OFFICE

JOHN F. HASLETT, OF SAUSALITO, CALIFORNIA

CONTAINER

Application filed March 23, 1927. Serial No. 177,572.

This invention relates to containers, and particularly to containers for substances bearing radium emanations. It is known that if a substance, such as water, is placed in a container having therein a radioactive material, the substance or water becomes charged with the rays or emanations from the radioactive materials, such rays or emanations being commonly called niton or niton gas. Liquids or substances so charged have medicinal uses, but the niton gases or emanations heretofore have soon escaped from the liquids or substances with a loss or decrease in the medicinal property of the liquids. If this loss of niton gases or emanations can be reduced, the medicinal effectiveness of the charged liquids or substances can be increased. The loss has been particularly noticeable in jars used to charge drinking water with radium emanations, where a cover to keep out dust is provided for the jar opening through which water, or the substance to be charged, is added to the jar at intervals.

An object of the invention is to provide an improved container of this type, with which the loss of emanations through the filling or other openings will be largely if not entirely prevented; which may be easily and conveniently handled and moved; and with which the entrance of dust to, or contamination of the contents of, the container will be effectively prevented.

A further object of the invention is to provide an improved container for charging substances with radium emanations; with which the radioactive lining will be fully protected from injury at the open end of the container, and escape of the emanations reduced or prevented.

40 A further object of the invention is to provide an improved method of preventing loss of radium emanations from containers in which substances charged with radium emanations may be stored.

45 A further object of the invention is to provide an improved means for accomplishing any of the above objects, which will be relatively simple, practical, effective and inexpensive.

50 Further objects and advantages will be

apparent from the following description of an embodiment of the invention, and the novel features will be particularly pointed out hereinafter in connection with the appended claims.

55

In the accompanying drawings:—

Fig. 1 is an elevation, largely in section, of a jar or container constructed in accordance with the invention;

Fig. 2 is a partial sectional elevation of the 60 same, on a somewhat larger scale to better illustrate the function of the liquid seal;

Fig. 3 is a plan of the under face of the cover of the jar; and

Fig. 4 is a plan of the open end of the jar. 65

In the illustrated embodiment of the invention, a shell, jar, or receptacle 1 may be formed of any suitable material, such as pottery, and may have a suitable faucet 2 by which liquid contents of the receptacle may be withdrawn. The upper end of the jar opens upwardly and is provided with an inwardly extending flange 3 which somewhat restricts the opening of the receptacle or shell, 70 and provides a thickened wall portion at the open end of the shell or receptacle. The upper end face or wall of the receptacle or shell, as thickened by the flange 3, is provided with a peripherally continuous groove 4 which opens upwardly and surrounds the restricted opening formed by the flange 3. The portion of the shell or receptacle forming the inner side wall of the groove 4 is formed to permit the passage of any surplus liquid 75 which may be in the groove, into the interior of the shell or receptacle before it can overflow the outer side wall of the groove. This result may be conveniently, and preferably is, obtained by placing the upper edge 5 of the 80 inner side wall of the groove 4 at a lower level than the upper edge of the outer side wall.

The shell or receptacle 1 is also provided with a suitable closure or cover 6 which preferably rests upon the upper edge of the outer side wall of the groove, so as to be supported thereon, and the under face of this cover is provided with a depending, continuous flange 7 which depends into and is received in the 90 groove 4 whenever the cover is in closed position.

95

100

tion. Thus when the cover is in closed position, the flange 7 will extend into the groove 4 and form, with any liquid in that groove, a liquid seal preventing the passage of air beneath the cover to and from the interior of the receptacle. Inasmuch as the cover rests upon the upper edge of the outer wall of the groove, the groove will be closed largely to the outside air and therefore evaporation of the liquid forming the seal in the groove 4 will be largely prevented. Any surplus of liquid in the groove will automatically overflow into the interior of the receptacle.

The under face of the cover 6, particularly the area enclosed or bounded by the flange 7, is formed to direct into the groove 4, that is, downwardly along the flange 7, any moisture which condenses or collects upon the under face of the cover. Preferably this formation is obtained by making the under face of the cover, that is, the area thereof bounded by the flange 7, substantially concave and sloping toward the flange 7, so that any moisture condensing or collecting on the under face of the cover will descend by gravity and capillary action into the groove 4 sufficiently to provide or replenish the liquid therein forming the liquid seal. Any surplus will flow automatically over the inner wall of the groove 4 into the receptacle. The cover is also preferably made of pottery, and it has been found that moisture tends to collect more readily upon pottery surfaces than upon surfaces of many other materials. The collection of globules of such moisture is illustrated at 8 in Fig. 2, the liquid forming the seal in the groove being indicated at 9.

I have found that when the substance or material placed in the receptacle is a liquid, or one having natural moisture, the moisture evaporating therefrom into the air of the receptacle from this substance or liquid will to some extent condense or collect upon the under face of the cover as shown in Fig. 2, and descend into the groove 4 to provide a continuous supply of liquid for the seal automatically. However, one may place a liquid for the seal in the groove 4 at intervals if desired, and if the groove should be filled to such an extent that some of the liquid displaced by the flange of cover as it descends into the groove will overflow, this overflow will be into the receptacle and not over the outer wall or surface of the receptacle where it might drop upon a supporting table and injure the same or present an unsightly appearance. The liquid seal also effectively prevents the entrance of dust to the receptacle.

I have found that radium emanations have a greater affinity for air than for water, and heretofore there has been some loss of emanations through the air beneath the cover. I have found that with the liquid seal for the cover, the loss of emanations from the jar is

very greatly reduced, if not entirely prevented.

In the preferred embodiment of the invention, the receptacle is provided with a lining 10 of radioactive material such as a cement, or porous clay or other binder material, containing particles of a radioactive substance, such as radium ore. These radioactive substances give off rays or emanations which charge the contents of the receptacle. By preventing loss of the emanations from the contents of the receptacle, a greater degree of radioactivity or greater charging of the contents may be obtained. This lining extends to the flange 3, but is of a thickness less than the extent to which the flange 3 extends into or across the open end of the receptacle, so that there will be a slight internal rib around the interior of the open end of the container. Such receptacles, particularly when made of pottery, are usually heavy and difficult for one to handle, particularly for housewives, and this inwardly extending bead provides a very effective handle by which one may lift or move the receptacle without danger of the hands slipping therefrom, especially when one grasps the receptacle at its open end. This flange 3 further acts as a buffer for the radioactive lining 10, and by preventing direct contact of the cover with the radioactive lining, the flange 3 protects the upper end edge of the radioactive lining, and prevents chipping of the same through shocks such as may be caused by the placing of the cover in position too violently.

Receptacles or jars such as have been herein described and illustrated are very useful in the charging of drinking water, and for best results should be kept substantially filled with drinking water. For this reason it is customary with many users to fill the receptacle every time that drinking water is removed, or at frequent intervals. The water is therefore usually close to the top, and escape of the emanations which are also called niton or niton gas, will now be largely prevented. The moisture of the air in such a water jar or receptacle collects in globules upon the under face of the cover 6, and settles into the groove 4, thus keeping the groove filled at all times with sufficient liquid to effectively seal the joint between the cover and the receptacle.

It will be obvious that various changes in the details, which have been herein described and illustrated in order to explain the nature of the invention, may be made by those skilled in the art within the principle and scope of the invention as expressed in the appended claims.

I claim:

1. A container for the storage of a substance bearing radium emanations, which comprises a receptacle having an open upper

end with an upwardly opening, continuous groove surrounding the opening, and a cover resting upon the outer wall of the groove when in closed position over said opening and having a flange portion depending into the groove to co-act with a liquid in said groove and seal the opening against the loss of radium emanations through the space between the cover and receptacle, the cover preventing the access to the groove of outside air tending to evaporate the moisture in the groove and forming the liquid seal, the under face of said cover within and adjacent said flange being inclined toward the flange so as to conduct into the groove moisture collecting upon the under face of the cover, the inner wall of the groove being formed to conduct into the receptacle any surplus moisture in said groove, before such surplus can overflow the outer wall of the groove.

2. A container for charging substances with radium emanations, comprising a shell having an open upper end with an inwardly extending flange portion restricting the opening, a cover for said shell, and a lining containing radio active material covering the inner surface of said shell, extending to said flange portion, but of less thickness than the inward extension of said portion, whereby said flange portion protects the lining against injury, and also serves to prevent slippage of one's hands grasping the open end of the shell while moving or handling the shell.

In testimony to the foregoing I hereto sign my name.

JOHN F. HASLETT.
